UNITED STATES PATENT OFFICE.

THOMAS A. W. DWYER, OF PASSAIC, NEW JERSEY, ASSIGNOR, BY DIRECT AND MESNE ASSIGNMENTS, OF SEVEN-SIXTEENTHS TO HANS O. SCHUNDLER, OF MADISON, NEW JERSEY, ONE-EIGHTH TO WILLIS H. BOTSFORD, OF NEW YORK, N. Y., AND ONE-SIXTEENTH TO ARCHIMEDES J. JAMES, OF NEW YORK, N. Y.

ROTARY RETORT.

Application filed August 15, 1924. Serial No. 732,177.

The invention relates to a rotary retort which is of general utility where materials are to be subjected to a fractionating treatment, and has for a primary object to provide such a retort which will enable the fractionated vapors to assume a stratified formation in the retort and be drawn off therefrom in such condition, thereby facilitating the ultimate separation of the vapors. The 5 retort structure herein described also has the advantage, for general heating purposes, of heating the material which passes therethrough more evenly and uniformly.

Further objects and advantages of the invention will be in part obvious and in part 15 specifically pointed out in the description hereinafter contained, which, taken in connection with the accompanying drawings, discloses a preferred embodiment thereof; 20 such embodiment, however, is to be considered merely as illustrative of its principles.

In the drawings:

Fig. 1 is a longitudinal section of a retort constructed in accordance with the invention.

25 Fig. 2 is a transverse section taken along the line 2—2 of Fig. 1.

Fig. 3 is a transverse sectional view taken on line 3—3 of Fig. 1 and looking in the direction of the arrows.

30 Fig. 4 is an enlarged longitudinal sectional view of the delivery end of the retort, illustrating more particularly a form of gas-tight expansion joint which may be used in connection with the retort.

35 The retort is of the horizontal type, and is rotatably mounted within a suitable oven 1, as by means of a suitable number of roller bearings 2 and 3, engaging rings 4 and 5 respectively located near the entrance and de-

40 liveries ends of the retort casing 6. The retort is rotated in any suitable manner, as by means of a gear 7, at its entrance end near the ring 4, and engaging a pinion (not shown).

45 The material is suitably fed into the retort casing, for example, by a hopper 8 communicating through a conduit 9 at its lower end with the entrance end of the retort, the material being pushed forward through conduit 9 by some such device as a reciprocable piston 10 mounted therein.

50 If the material be fed through the retort mechanically, as by worms or fins, the travel of the material through the retort is quite

irregular, and the material is unevenly heated. The uneven heating prevents uniform fractionation, and the vapors cannot stratify under the circumstances. Furthermore, the hot fins or worms often crack the vapors upon coming into contact with them, destroying the possibility of stratification. 55 The overheated portions of the material being fed through the retort also in many instances form hard deposits upon the interior of the casing which are difficult to remove. 60

According to the present invention the 65 retort casing is made of such a shape that the materials to be fractionated are fed through the retort by its rotary motion alone, without the aid of mechanical feeding devices such as worms or fins, the rotary motion of 70 the still causing the materials to be continually shifted or turned over in passing through the retort, whereby the material is uniformly heated.

To carry out the above objects, I construct 75 the retort casing 6 in the form of the frustum of a pyramid. The retort casing 6 is rotated at slow speed, for example, two or three revolutions per minute, and the material which is fed into conduit 9 by piston 10 tends to fall to the bottom side of the casing into a pile of the shape shown in Fig. 1. As the retort rotates, owing to its polygonal cross section, the material remains substantially 80 stationary with regard to the side walls until the bottom side wall has turned upward to an angle greater than the angle of repose of the material being treated; at this point the material shifts quite suddenly with respect to the walls of the retort, with the result that 85 such material is well turned over, the parts of the material which previously were innermost, falling downwardly into contact with the then bottom side of the retort, and the parts of material which previously had been in contact with the side walls and therefore subjected to the most intense heat, dropping down on top of the body of the material.

Thus the rotary motion of the retort produces 90 constant shifting or turning over of the material, which insures uniform heating thereof, and prevents the burning of portions of such material against the side walls of the retort, such as would occur, for example, in a circular or conical retort, where the body 95 of material being treated would tend always

to slip down the curved walls of the retort without the different parts of the material shifting to any substantial extent with regard to each other. The continual shifting 5 of the material which is brought about by the form of retort above described also produces dependable and sharply defined fractionation, and the vapors it has been found 10 stratify evenly in the upper part of the retort, from whence they may be withdrawn as they are formed in such condition as to promote 15 their separation.

The forward feed of the material through the retort is brought about merely by the 15 natural forward movement caused by the rotation of the retort, the piston being operated only at sufficient speed to replace the material in the conduit 9 as it gradually falls off into the casing 6.

20 I do not claim in the present application any processes which may be performed by the retort herein described and claimed, certain of such processes, as well as certain modifications and improvements in the apparatus involved, being claimed in my copending application Serial Number 739,451, filed September 24, 1924, entitled "Process and apparatus for producing coke", and in my copending application, Serial Number 82,440 25 filed January 20, 1926, entitled "Method and apparatus for distillation".

The material passes along the casing 6 in the manner above described to its delivery end, from whence it may be ejected as by a 25 suitable conduit 11 in a fixed housing 12. It will be obvious that as many stills of the above nature as may be desired may be connected in series and operated at different temperatures, fractionating at successive stages 40 according to the nature of the material to be fractionated. The apparatus is adapted to the fractionation of solid or liquid materials, the latter being mixed with a suitable carrier substance in being passed through the retort. 45 This carrier substance may be inert matter, or if desired may be of such nature that it, as well as the liquid, will be fractionated. As a carrier for petroleum oils, for example, sand may be employed, or if desired fine coal, 50 the volatiles of which will be distilled off at the requisite temperatures. It should be understood that the principles of the retort may also be applied to the fractionation of gases.

The fractionated vapors may be drawn off 55 through a suitable pipe 13 connected to housing 12 at the delivery end of the retort, from whence the vapors may be led to suitable separating apparatus, or subjected to other desired treatment which need not be described herein. Usually the pipe 13 will be subjected to negative pressure to withdraw the 60 vapors from the retort as they are formed.

It will be understood that different shapes 65 of retort may be employed depending upon the materials to be fractionated. For most

purposes I have found the hexagonal shape illustrated to be advantageous, the use of a retort in the shape of a many-sided polygon approaching too nearly circular cross section to adequately shift and turn over the material, while the use of a three or four-sided pyramidal shape for some purposes tends to create too much dust within the retort, although it will serve to mix the materials thoroughly for uses where the dust is not objectionable. 70 75

The temperature within the retort casing 6 is controlled by a pyrometer inserted through an opening 26 in the housing 12, into the fractionated vapors, the amount of heat 80 supplied by the oven being regulated in any suitable manner (not illustrated) from the pyrometer.

According to the speed of rotation of the retort, the rate of passage therethrough of the material may be adjusted as desired, which in combination with the temperature control above mentioned, makes the apparatus properly adjustable to variable conditions 85 of operation. 90

For most purposes the entrance end of the retort will be sufficiently sealed as regards the hopper 8 and conduit 9, by the material being fed through. The entrance end of the retort casing may also be suitably sealed to provide 95 a fluid-tight joint, as by means of an end plate 14 which is fixed on the walls of the conduit 9 and carries a gland 15 holding packing material such as asbestos contained within member 14. As shown, a ring 17 is mounted 100 on the entrance end of casing 6 to support the members 4 and 7 above described as well as to turn truly within the gland 15 and packing material 16. At its delivery end the retort may be sealed as by providing the 105 water seal indicated diagrammatically at 18 for the conduit 11.

The apparatus is also arranged to permit 110 expansion and contraction due to temperature changes while retort maintaining a fluid-tight seal for the interior of the retort. In the present embodiment the entrance end of the retort is relatively fixed as regards longitudinal movements due to the fact that the members 2 are flanged and thus hold the ring 14 at all times in substantially the same plane. At the delivery end of the apparatus, however, the ring 5 may slide back and forth longitudinally of the retort, with regard to the rollers 3. A cylindrical casting 19 surrounds 115 the casing 6 near its delivery end and is longitudinally slidable with regard to certain parts associated with the housing 12 to provide a fluid-tight joint while still permitting the member 19 to rotate with the retort casing. 120

The illustrated form of joint is shown more in detail in Figure 4 from which it will be noted that the housing 12 has connected thereto at its inner end an annular end casting member 20 which surrounds the casting 125 130

19 and is provided with an internal shoulder 21. The casting 19 is also provided with an annular gland-like member 22 opposed to the shoulder 21 above mentioned, and between these two opposed parts a suitable packing material 23 such as asbestos is interposed. Preferably a pair of wear rings 24, in the form of split rings, are interposed between the parts 21 and 22 and the packing material, the compression on the packing material being sufficient at all times to maintain the joint substantially fluid-tight.

The joint above described permits the retort casing 6 to adjust itself to temperature changes without opening the interior of the retort to the atmosphere; furthermore, at the slow speed of rotation the joint does not cause undue friction even when the compression on the packing is increased due to expansion. Preferably an annular guard flange 25 is secured to the casing member 20.

With a retort of the above construction, the upper part of the space within the casing 6 is entirely free of obstructions or unbalanced conditions tending to cause the diffusion between or intermingling of the fractionated vapors. The sealing of the joints of the apparatus also permits the partial vacuum in pipe 13 to draw off the vapors in a stratified formation which the retort permits them to assume.

While the specific embodiment of the invention has been described it will be obvious that many changes may be made therein without departing from its principles as defined in the appended claims.

I claim:

1. A retort of the horizontal type, comprising a hollow casing in the shape of a frustum of a pyramid, bearing members for rotatably supporting said casing in a substantially horizontal position, means for heating said casing exteriorly, means for feeding material to be fractionated to said casing whereby said material is turned over and advanced through the casing by rotary motion to produce stratified vapors in the upper portion of the casing, and a conduit associated therewith adapted to draw off vapors from within the upper part of the delivery end of said casing.

2. A retort of the horizontal type, comprising a hollow casing of polygonal cross section as regards its interior walls, bearing means for rotatably supporting said casing in a substantially horizontal position, means

for heating said casing exteriorly, means for feeding material to be fractionated to said casing whereby said material is turned over and advanced through the casing by rotary motion to produce stratified vapors in the upper portion of the casing, and a conduit associated therewith adapted to draw off vapors from within the upper part of delivery end of said casing.

3. A retort of the horizontal type, comprising a hollow casing of polygonal cross section as regards its interior walls, bearing means for rotatably supporting said casing in a substantially horizontal position, means for heating said casing exteriorly, means for feeding material to be fractionated to the entrance end of said casing whereby said material is turned over and advanced through the casing by rotary motion to produce stratified vapors in the upper portion of the casing, a fixed housing enclosing the delivery end of said casing, said housing having associated therewith conduits adapted respectively to draw off vapors from within the upper part of said casing and to receive liquid and solid materials discharged therefrom.

4. A retort of the horizontal type, comprising a hollow casing of polygonal cross section as regards its interior walls, bearing means for rotatably supporting said casing in a substantially horizontal position, means for heating said casing exteriorly, means for feeding material to be fractionated to said casing whereby said material is turned over and advanced through the casing by rotary motion to produce stratified vapors in the upper portion of the casing, a conduit associated therewith adapted to draw off vapors from within the upper part of said casing, and means for effecting a substantially fluid tight seal for said casing.

5. A retort of the horizontal type, comprising a hollow casing in the shape of a frustum of a pyramid, as regards its interior walls, means for rotating said casing, means for feeding material to be fractionated into the smaller end of said casing, means for drawing off vapors from within the upper part of the larger end of said casing, means for receiving solids discharged from the larger end of said casing, and means for heating said casing exteriorly.

In testimony that I claim the foregoing, I have hereunto set my hand this 8th day of August, 1924.

THOMAS A. W. DWYER.
